ATTORNEY'S

UNITED STATES PATENT OFFICE

JOHN WINTER, OF ALBION, MICHIGAN

HEATING STOVE

Application filed March 25, 1929. Serial No. 349,562.

The main object of this invention is to provide a heating stove with an improved construction of sheet metal heating drum.

Objects pertaining to details and economies of construction and operation will definitely appear from the description to follow. A stove embodying a preferred form of my invention is clearly illustrated in the accompanying drawing, in which:

10 Fig. 1 is a perspective view of a stove having my improved heating drum structure.

Fig. 2 is a central vertical sectional view through the heating drum and firepot portion on line 2—2 of Fig. 3.

15 Fig. 3 is a horizontal sectional view taken on the broken line 3—3 of Fig. 2.

The parts will be identified by their numerals of reference which are the same in all the views.

20 1 is the stove base of usual construction with ash pit door and damper.

25 2 is the firepot with an annular collar flange 21 spaced a considerable distance from the top to form an attaching rim for the combustion chamber. 3 is the sheet metal combustion chamber bolted to the top rim of the firepot and with inturned top flange 31. 32 is the flue opening therethrough toward the bottom rear side thereof. 4 is the heating drum with inturned bottom flange 41 and with straight top which surrounds the combustion chamber 3 forming a broad circulating passage for the products of combustion in order to insure thorough heat delivery therefrom. Inturned flange 41 rests upon the ring plate 5 which is supported on the flange 21 of the firepot. Bolts 42 bolt the parts together. The periphery of the ring 5 projects to finish the bottom of the radiating drum being in a half round form and preferably nickel-plated.

30 The feed door casing 6 encases the door opening between the walls of the combustion chamber and the heating drum. The door 40 45 50 55 60 65 70 75 80 85 90 95 100

sage for the products of combustion above and below the door casing 6, as seen in Fig. 2.

8 is a sheet metal top plate over both the combustion chamber and heating drum and is provided with a smoke pipe collar 9. This plate is either bolted or spot welded to the flanged walls of the combustion chamber and the radiating drum. The finishing ring 10 rests upon the top. A top plate 11 of cast metal finishes the top of the stove and may be provided with a griddle 12.

A vertical partition 13 is between the flue opening 32 and the smoke pipe collar 9 so that when the products of combustion enter the heating drum through the smoke passage 32 they expand and fill the space and are somewhat checked in their flow in the space 14 by the presence of the door casing 6 and pass the door to the space 15, and thus have a wide distribution and slow flow which enables the delivery of the heat from the products of combustion by radiation and convection so that the temperature of the products of combustion at smoke collar 9 is only sufficient to meet the requirements for effective chimney draft.

The stove, when operated to its reasonable capacity, is very economical of fuel because of the opportunity of complete heat transfer due to the full expansion and circulation in a comparatively thin layer of the entire products of combustion without the necessity of any direct flue and consequently without the occasion of any losses thereby.

My structure, of course, can be considerably modified in its details without departing from my invention. I desire, however, in view of the economy of construction to claim the structure specifically and also broadly as pointed out in the appended claims.

Having thus described my invention, what I claim as new and desire to secure by Letters Patent, is:

1. In a heating stove, the combination of a firepot with collar flange near its top; a sheet metal combustion chamber having an inturned top flange bolted thereto at its bottom edge and having a lateral flue opening near its bottom at the back, a supporting

plate ring disposed on the flange at the top of the firepot, a heating drum surrounding said combustion chamber with inturned bottom flange resting on the supporting plate ring and bolted thereto, a feed door frame through the said walls of the combustion chamber and heating drum, a top plate over the entire structure and suitably bolted thereto and having a smoke collar, and a vertical partition between the radiating drum wall and the combustion chamber wall disposed between the flue opening in the combustion chamber and the smoke collar in the top plate, whereby the products of combustion are delivered into the heating drum and circulated entirely around the same to the smoke collar to insure heat delivery before they are discharged.

2. In a heating stove, the combination of a firepot with collar flange near its top, a sheet metal combustion chamber having a lateral flue opening near its bottom at the back, a supporting plate ring on the flange at the top of the firepot, a heating drum surrounding said combustion chamber with inturned flange resting on the supporting plate ring and bolted thereto, a feed door frame through the said walls of the combustion chamber and heating drum, a top plate over the entire structure and suitably bolted thereto and having a smoke collar, and a vertical partition between the radiating drum wall and the combustion chamber wall disposed between the flue opening in the combustion chamber and the smoke collar in the top plate, whereby the products of combustion are delivered into the heating drum and circulated entirely around the same to the smoke collar to insure heat delivery before they are discharged.

3. In a heating stove, the combination of a firepot with collar flange near its top, a sheet metal combustion chamber having a lateral flue opening near its bottom at the back, a supporting plate ring on the flange at the top of the firepot, a heating drum surrounding said combustion chamber with inturned bottom flange resting on the supporting plate ring and bolted thereto, a top plate over the entire structure and suitably bolted thereto and having a smoke collar, and a vertical partition between the radiating drum wall and the combustion chamber wall disposed between the flue opening in the combustion chamber and the smoke collar in the top plate, whereby the products of combustion are delivered into the heating drum and circulated entirely around the same to the smoke collar to insure heat delivery before they are discharged.

4. In a heating stove, the combination of a firepot with collar flange near its top, a sheet metal combustion chamber having a lateral flue opening near its bottom at the back, a heating drum surrounding said combustion

chamber, a top plate over the entire structure and suitably bolted thereto and having a smoke collar, and a vertical partition between the radiating drum wall and the combustion chamber wall disposed between the flue opening in the combustion chamber and the smoke collar in the top plate, whereby the products of combustion are delivered into the heating drum and circulated entirely around the same to the smoke collar to insure heat delivery before they are discharged.

In witness whereof I have hereunto set my hand.

JOHN WINTER.
